(57) **CLAIM**

The ornamental design for a knee pad for a knee or the like, as shown and described.

DESCRIPTION

FIG. 1 is a perspective view of a knee pad for a knee or the like in place on a knee, and showing my new design;

FIG. 2 is a top view of the knee pad for a knee or the like;

FIG. 3 is a front view thereof;

FIG. 4 is a left side view thereof;

FIG. 5 is a back view thereof;

FIG. 6 is a right side view thereof; and

FIG. 7 is a bottom view thereof.

FIG. 8 is a perspective view of an alternative embodiment of a knee pad for a knee or the like showing an alternative design;

FIG. 9 is a top view of the embodiment of FIG. 8;

FIG. 10 is a front view thereof;

FIG. 11 is a left side view thereof;

FIG. 12 is back view thereof;

FIG. 13 is a right side view thereof; and,

FIG. 14 is a bottom view thereof.

The broken line showing of a knee is for illustrative purposes only and forms no part of the claimed design.

The broken lines shown on the knee pad in the drawing are understood to represent stitching.
